UNITED STATES PATENT OFFICE

BERNHARD SPERBER, OF BERLIN, GERMANY

EGG-BOILING FRAME

Application filed July 23, 1930, Serial No. 470,148, and in Germany May 24, 1930.

The present invention relates to egg-boiling apparatus, and more particularly to a frame or stand which enables the eggs to be introduced into and removed from the saucepan or other vessel employed in extremely ready fashion, is very cheap to produce, and in the dismantled condition may be despatched through the post, etc., without occupying any considerable amount of space.

10 This is accomplished by the fact that the platforms or holding plates for the eggs are mounted on a central column or post, which is furnished with fixed supports for the single platforms, so that each platform is held 15 in position by means of a special support on the column or post.

A possible form of embodiment of the invention is illustrated by way of example in the accompanying drawings, which shows 20 the stand or frame as comprising in substance the central column or post with two platforms for holding the eggs.

Fig. 1 is an elevational view of the holder, partly in section,

25 Fig. 2 a plan view, also in part section, and

Fig. 3 a modified form of the connection between the platform and the post.

Referring now to Figs. 1 and 2, *a* is the central column or post which, in the particular embodiment illustrated in the drawings, is shown as being of square cross-section. The same is furnished on each of the four sides, at the centre, with a groove, the two oppositely disposed pairs of grooves being carried to different extent towards the foot end of the column. The two grooves *b*¹ serve for guiding the lower platform *c*¹, while the two grooves *b*² are for guiding the upper platform *c*². Each platform according to the drawings is furnished with four openings *d*. In place of the four openings it is naturally also possible to provide any other convenient number, which do not essentially require to be merely distributed about a circular path as in the specific embodiment shown. *e* is the bottom of the stand, which may be secured to the lower end of the column, for example by means of a screw *f*. The bottom *e* is perforated, and furnished with a suitable number of feet *g* to avoid placing the bottom

of the frame or stand in immediate contact with the bottom of the saucepan. The feet *g* may be of any desired height, so that if necessary the bottom *e* may also be employed for supporting eggs in similar manner to 55 the platforms *c*¹ and *c*².

The column or post *a* is preferably made of wood, and if desired, may be furnished at the upper end with a central boring *h* for reception of a sand-glass, such as indicated in the drawings by *i*.

The detachable arrangement of the platforms on the column or post enables the apparatus to be packed within a small space.

The manipulation of the apparatus will be 65 readily apparent from the drawings. It will be recognized that if for example it is desired to boil a maximum number of four eggs merely the lower platform *c*², or the bottom *e* respectively, will be employed, while the 70 second or any additional platforms will only be taken into use if a greater number of eggs are required. In other words the eggs will be situated in the holder commencing at the lowest point available in order to avoid necessity for an undue amount of water for boiling purposes.

The supports for the platforms are shown in Figs. 1 and 2 as consisting of abutments or shoulders on the column engaging with 80 teeth or other projections fitting into the grooves. These supports may naturally also be formed in other manner, for example in the case of any cross-sectional form of the column which is not round by means of incisions in the thicker part of the column, as shown in Fig. 3, where the recess in the platform is shown as being somewhat twisted in relation to the corresponding cross-section of the column, the possibility of this twist 85 being provided by the incisions in the column.

It will be understood that no restriction is made to the specific form of embodiment shown, and that various modifications are quite possible within the meaning of the 90 above description and the annexed claims without departing from the spirit of the invention.

Thus, for example, I do not restrict myself to the use of two platforms, but may also 100

- employ any other convenient number, and if desired merely one platform. Nor do I make any restriction to provision for four eggs in each platform, and obviously any other convenient number of openings may be provided either in one or more circular rows or in any other appropriate disposal utilizing the available space to the best advantage.
5. In a form of embodiment of an egg-boiling frame, a central column, platforms furnished with holding apertures for the eggs, a bottom supporting the said column and having additional holding apertures for eggs, feet on the said bottom, oppositely disposed grooves in the said column, abutments at the lower extremities of the said grooves, projections in recesses of the said platforms adapted to thrust against the said abutments and detachably hold the said platforms in position, and a sand glass mounted at the top of the said column.
6. In a form of embodiment of an egg-boiling frame, a central column, a bottom supporting the said column, feet on the said bottom, longitudinal grooves provided in staggered relation to each other in the said column, abutments at the lower extremities of the said grooves, platforms furnished with holding apertures for the eggs, projections in recesses of the said platforms adapted to thrust against the said abutments and detachably hold the said platforms in position, and a sand glass mounted at the top of the said column.
7. In a form of embodiment of an egg-boiling frame, a central column having diametrically opposed indentations providing supporting surfaces intermediate its ends, and a platform having apertures for holding eggs and a central opening for receiving said column when the platform is slid upon the same, portions of said platform adjacent said central opening resting upon the said diametrically opposed surfaces of said column to support said platform above the bottom of said column.
8. An egg-boiling frame comprising a central column having diametrically opposed indentations providing supporting surfaces intermediate its ends, and a platform having apertures for holding eggs and a central opening for receiving said column when the platform is slid upon the same, portions of said platform adjacent said central opening resting upon the said diametrically opposed surfaces of said column to support said platform above the bottom of said column.
9. An egg-boiling frame comprising a central column of non-circular cross section, a platform provided with apertures for holding eggs and having a central opening adapted to be slid on said column, said central column being provided with transverse incisions intermediate its ends at diametrically opposed points, whereby said platform may be supported above the lower end of said column by sliding said platform over said column into position opposite said incisions and turning said platform about the axis of said column to introduce the same into said incisions.
10. An egg-boiling frame comprising a central column of non-circular cross section, a platform provided with apertures for holding eggs and having a central opening adapted to be slid on said column, said central column being provided with transverse incisions intermediate its ends at diametrically opposed points, whereby said platform may be supported above the lower end of said column by sliding said platform over said column into position opposite said incisions and turning said platform about the axis of said column to introduce the same into said incisions.
11. An egg-boiling frame, a central column, a perforated bottom supporting the said column, feet on the said bottom, platforms furnished with holding apertures for the eggs, oppositely disposed grooves in the said column, abutments at the lower extremities of the said grooves, and projections in recesses of the said platforms adapted to thrust against the said abutments and detachably hold the said platforms in position.
12. An egg-boiling frame, a central column, a perforated bottom supporting the said column, feet on the said bottom, platforms furnished with holding apertures for the eggs, oppositely disposed grooves in the said column, abutments at the lower extremities of the said grooves, and projections in recesses of the said platforms adapted to thrust against the said abutments and detachably hold the said platforms in position, and a sand glass mounted at the top of the said column.
